UNITED STATES PATENT OFFICE.

E. VALENTINE AND M. T. RIDOUT, OF MILWAUKEE, WISCONSIN, ASSIGNEES
TO THEMSELVES AND WILLIAM BECK, OF SAME PLACE.

IMPROVEMENT IN BENDING METALLIC SPOUTS.

Specification forming part of Letters Patent No. 37,205, dated December 16, 1862.

To all whom it may concern:

Be it known that we, E. VALENTINE and M. T. RIDOUT, both of Milwaukee, in the county of Milwaukee and State of Wisconsin, have invented a new and Improved Machine for Bending Metallic Spouts; and we do hereby declare that the following is a full and exact description thereof, reference being had to the accompanying drawings, and to the letters of reference marked thereon.

Figure 1 is a side view of our improved machine when not in use; Fig. 2, a side view of the same, showing the position of its several parts when the swaging apparatus is in operation; Fig. 3, a top view of the machine when in the position indicated by Fig. 2; Fig. 4, a transverse section of the same in the direction indicated by the line $x\ x$ of Fig. 1, and Fig. 5 a transverse section in the line $y\ y$ of Fig. 2.

Similar letters indicate similar parts in each of the figures.

The nature of our invention consists in the use of an elastic laminated core or mandrel, in connection with a swaging apparatus, for the purpose of quickly and accurately bending metallic pipes or spouts for tea-pots, coffee-pots, &c.

A bench or table composed of the top A and legs B receives and supports the respective parts of our machine for bending metallic pipes or spouts. Secured to and rising from this table A are the following parts of our machine, viz: the uprights C C and D, the guiding and controlling arc E, the longitudinal guiding-block F in the vertical plane of the arc E, and the longitudinal shaping-block G, running parallel with the arc E and block F, as represented in Figs. 1, 2, and 5 of the accompanying drawings. The upright D is made to terminate in a pin, a, which receives and serves as a pivot for the inner end of the lever-arm H, which vibrates horizontally upon the supporting-bar e, placed upon the uprights C C. To this horizontal lever H is jointed the core or mandrel J, which rests upon the upper surface of the forming and shaping block G. The end of this shaping-block G farthest removed from the horizontal lever H is curved in the form to be imparted to the metallic spout. A transverse aperture is made in the bench A at a point corresponding with the

intersection of the curved end of the shaping-block with its upper straight surface. This transverse aperture terminates at the base of the outer face of the shaping-block G on the one side, and of the guiding-block F on the other, and coincides accurately with equal vertical apertures or notches d, Fig. 2, formed opposite to each other in the said blocks. These vertical notches in the blocks F and G form bearings for the ends of a sliding journal-box, K, Fig. 4, which plays freely up and down therein through this transverse aperture. This sliding journal-box is supported in an elevated position by the spiral spring L, the lever M, and the bridle-piece N, or their equivalents, all secured under the bench A, as is represented in Fig. 4. The resistance of the spring L may be overcome and the journal-box K, with its attachments, be forcibly drawn down by means of a treadle, P, and connecting-rod O. Its descent, however, is arrested by the stops Q Q on the outer faces of the blocks F and G, which stops catch and embrace the ends of the pin e, upon which is jointed (within the journal-box K) the main swaging-lever R. This main lever R vibrates freely in the longitudinal space between the parallel blocks F and G, although made to fit closely therein, as represented in Fig. 3. The vibratory movement of this main lever is arrested by the stops f and f, fixed upon the controlling-arc E.

Upon that face of the journal-box K more remote from the curved end of the shaping-block G is secured an upright retaining-hook, S, which is made to bend over the upper surface of this shaping-block G, as represented in Fig. 5. A grooved swaging-wheel, T, is firmly attached to the front face of the main lever R, directly over the shaping-block G, by means of the embracing-box g, which is combined with a sliding bar, i, on the opposite side of the lever, as represented in Figs. 3 and 4. The shank k, which projects from the inner side of the embracing-box g, passes through a longitudinal slot, m, Fig. 4, in said lever R, and is fastened and secured to the sliding bar i by a key or other suitable device. The inner journal projection of the swaging-wheel T also passes freely through a second longitudinal slot, n, Fig. 4, in the lever R, and is sup-

ported by means of a journal-aperture in the lower end of the sliding bar *i*, while the outer journal projection is similarly supported in the lower end of the embracing-box *g*. An elastic band, *p*, of india-rubber or other suitable material, is secured to the hook *S*, which rises immediately behind the swaging-wheel *T*, and is then carried forward under and over this wheel and fastened back to the end of a spring-bar, *W*, in the rear of the horizontal actuating-lever *H*. The upper surface of the shaping-block *G* is slightly concave, and is covered with a layer, *r*, of india-rubber or other elastic substance. The mandrel *J* is composed of a series of thin elastic metallic plates placed on either side of a core, *q*, of india-rubber or other elastically yielding material, the whole firmly secured to a suitable head, *s*; or this mandrel may be made in a solid piece of any substance possessing proper elasticity and solidity for the purpose required.

The mode of operating our improved machine is readily described as follows, viz: The core or mandrel *J* is thrown forward by the actuating-lever *H* until its end projects over the curve in the shaping-block *G* a distance equal to the length and extent of the curve desired in the spout to be bent. It is retained in this position by means of a pin, *l*, inserted in the supporting-bar *c*. A tube of tin or other metal of the required size, length, and taper, is then slipped over and upon the mandrel *J*, and by means of the treadle *P* and the sliding journal-box *K* the hook *S* and the swaging-wheel *T* are brought to bear firmly upon the upper surface of the tube, which is thereby pressed closely against the elastic surface of the shaping-block beneath it. By a movement of the main lever *R* the swaging-wheel is then carried forward, as represented in Fig. 2, bending the tube as it passes over it, the perfect regularity of its curve being secured and the evenness of its surface preserved by the resistance of the elastic core or mandrel *J* within, in connection with the elastic band *p* and cushion *r* without,

the tube. The tube or spout being thus easily and accurately bent in the desired shape, the core *J* is readily removed by a reverse movement of the actuating-lever *H*, and by relieving the treadle *P* from the pressure exerted thereon the retaining-hook *S* and swaging-wheel *T* are elevated and the finished spout at once released from the machine. These movements may all be executed with great rapidity and ease, thereby saving much labor, while producing cheaply a superior manufacture.

Having thus fully described our invention, what we claim therein as new, and desire to secure by Letters Patent, is—

1. The use of an elastic core or mandrel in the manufacture of curved metallic pipes or spouts, substantially in the manner hereinbefore set forth.

2. The use of a series of thin elastic metallic plates in the construction of a core or mandrel for the inflection of metallic spouts, substantially in the manner herein set forth.

3. When an elastic core or mandrel is used in the manufacture of curved metallic spouts, the use of a shaping-block, *G*, a retaining-hook, *S*, and a lever-actuated swaging-wheel, *T*, or their equivalents, when combined and arranged substantially in the manner and for the purpose herein set forth.

4. When a lever-actuated swaging-wheel *T* and shaping-block *G* are used in the inflection of metallic spouts, the use of an elastic protecting-band, *p*, and elastic cushion *r*, or their equivalents, when combined and arranged substantially in the manner and for the purpose herein set forth.

The above specification of our machine for bending metallic spouts signed and witnessed this 25th day of July, A. D. 1862.

E. VALENTINE.
M. T. RIDOUT.
